(57) **CLAIM**

The ornamental design for an induction cooktop, as shown and described.

DESCRIPTION

FIG. 1 is a top, front perspective view of an induction cooktop showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dash-dash broken lines illustrate portions of the induction cooktop that form no part of the claimed design. The dot-dash broken lines with zig-zag line features represent a symbolic break. The appearance of any portion of the induction cooktop between the dot-dash lines with zig-zag line features forms no part of the claimed design. The dot-dash broken lines forming a rectangle around the claimed article represent environmental structure and form no part of the claimed design.
